Primary Examiner — Abraham Bahta(74) *Attorney, Agent, or Firm* — Daniel J. Layden;
 Bandon J. Lee(57) **CLAIM**

The ornamental design for a trash bag, as shown and described.

DESCRIPTION

FIG. 1 is a front elevation view of the trash bag showing my new design, the back view being identical; and, FIG. 2 is an enlarged detailed view of the encircled portion in FIG. 1, shown for ease of illustration.

The straight broken line of FIG. 1 merely indicates the upper boundary of the pattern of the trash bag; the area extending beyond this boundary line is encompassed as part of the claimed design. The trash bag has no appreciable thickness. The dot-dash lines show no specific length and form no part of the claimed design.
